(57) **CLAIM**

The ornamental design for a garment, as shown and described.

DESCRIPTION

FIG. 1 is a Front perspective view of the garment as seen when worn by a person;

FIG. 2 is an enlarged Back perspective view of the garment as seen when worn by a person;

FIG. 3 is an enlarged Front elevational view of the garment;

FIG. 4 is an enlarged Bottom end view of the garment;

FIG. 5 is an enlarged Top end view of the garment;

FIG. 6 is an enlarged Right side view of the garment, the Left side view being opposite-hand view;

FIG. 7 is an enlarged Back elevational view of the garment;

FIG. 8 is a Front view of the garment as shown in FIG. 1; and, FIG. 9 is a Back view of the garment as shown in FIG. 2.

The broken line showing of a person is included for the purpose of illustrating environmental structure and forms no part of the claimed design.
